US00D961173S

(12) **United States Design Patent** (10) **Patent No.:** **US D961,173 S**
(45) **Date of Patent:** **** Aug. 16, 2022**

(54) **PET TOOTHBRUSH**

(71) Applicant: **Liqiang Zhang**, Shandong (CN)

(72) Inventor: **Liqiang Zhang**, Shandong (CN)

(73) Assignee: **Liqiang Zhang**, Shandong (CN)

(**) Term: **15 Years**

(21) Appl. No.: **29/778,251**

(22) Filed: **Apr. 12, 2021**

(51) **LOC (13) Cl.** **30-99**

(52) **U.S. Cl.**

USPC **D30/158; D30/199**

(58) **Field of Classification Search**

USPC D30/158, 199, 160; D4/104, 105, 108, D4/120, 119, 127, 128, 199, 132–134; D24/194, 214, 215; 15/167.1, 167.2, 15/104.2, 22.1, 106, 110, 71, 23, 143.1, 15/207.2, 160–164; 119/707, 710, 174; 433/1, 229; 134/6; 601/139–142; 606/234, 235

(57) **CLAIM**

The ornamental design for a pet toothbrush, as shown and described.

DESCRIPTION

FIG. 1 is a top view of a pet toothbrush showing my new design;

FIG. 2 is a bottom view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a perspective view thereof.

1 Claim, 4 Drawing Sheets
